(57) **CLAIM**

The ornamental design for a hinge, as shown and described.

DESCRIPTION

FIG. 1 is a front elevational view of a hinge in accordance with the present invention in its extended position;

FIG. 2 is a top plan view thereof, the bottom view being the mirror image thereof;

FIG. 3 is a rear elevational view thereof; and,

FIG. 4 is a side elevational view thereof, the opposite side being identical thereto.
